(57) **CLAIM**

The ornamental design for a golf bag assembly as shown and described.

DESCRIPTION

FIG. 1 is a top, front perspective view of our new design of a golf bag assembly;

FIG. 2 is a bottom, rear perspective view of the golf bag assembly shown in FIG. 1;

FIG. 3 is a front elevation view of the golf bag assembly shown in FIG. 1;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top, front perspective view of the golf bag assembly shown in FIG. 1 with a handle extended upward;

FIG. 10 is a top, front perspective view of a first alternate configuration of the golf bag assembly shown in FIG. 1;

FIG. 11 is a bottom, rear perspective view of the first alternate configuration of the golf bag assembly shown in FIG. 1;

FIG. 12 is a front elevation view of the first alternate configuration of the golf bag assembly shown in FIG. 1;

FIG. 13 is a rear elevation view thereof;

FIG. 14 is a right side elevation view thereof;

FIG. 15 is a left side elevation view thereof;

FIG. 16 is a top plan view thereof;

FIG. 17 is a bottom plan view thereof;

FIG. 18 is a top, front perspective view of a second alternate configuration of the golf bag assembly shown in FIG. 1;

FIG. 19 is a bottom, rear perspective view of the second alternate configuration of the golf bag assembly shown in FIG. 1;

(Continued)

FIG. 20 is a front elevation view of the second alternate configuration of the golf bag assembly shown in FIG. 1;
FIG. 21 is a rear elevation view thereof;
FIG. 22 is a right side elevation view thereof;
FIG. 23 is a left side elevation view thereof;
FIG. 24 is a top plan view thereof; and,
FIG. 25 is a bottom plan view thereof.
